GARMENT BRUSH

Esther Morgan, 901 N. Lincoln, Madison, S. Dak.

Filed Apr. 13, 1966, Ser. No. 1,865

Term of patent 14 years

(Cl. D9—2)

FIG. 7

FIG. 8

FIG. 9

FIG. 10

FIG. 1 is a top perspective view of a garment brush showing my new design;

FIG. 2 is a top plan view thereof;

FIG. 3 is a side elevational view thereof;

FIG. 4 is a bottom plan view thereof;

FIG. 5 is a rear elevational view thereof;

FIG. 6 is a front elevational view thereof;

FIG. 7 is a top plan view of a modified form of the design shown in FIGS. 1-6 incorporating the concepts of applicant's design;

FIG. 8 is a side elevational view thereof;

FIG. 9 is a bottom plan view thereof; and

FIG. 10 is an end elevational view thereof.

I claim:

The ornamental design for a garment brush, substantially as shown.
